(57) **CLAIM**

I claim the ornamental design for a feeding bottle, as shown and described.

DESCRIPTION

FIG. 1 is a top, front perspective view of a feeding bottle, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a cross-sectional elevation view of the feeding

bottle of FIG. 1, taken in the direction of line 6-6 of FIG. 2;

FIG. 7 is a top plan view of the feeding bottle of FIG. 1;

FIG. 8 is a bottom plan view thereof;

FIG. 9 is a top, front perspective view of the feeding

bottle of FIG. 1, shown in a first configuration of use; and,

FIG. 10 is a top, front perspective view of the feeding

bottle of FIG. 1, shown in a second configuration of use.

The broken lines in the drawings show environmental structure only and form no part of the claimed design.
